UNITED STATES PATENT OFFICE

JOSEPH ARTHUR DROUIN, OF WILLIMANTIC, CONNECTICUT

RAILROAD GATE

Application filed March 31, 1928. Serial No. 266,348.

My present invention has reference to an improved construction of railway crossing gates, my primary object being the provision of swingable gates arranged at the corners of a railway crossing and movable to provide a barrier on the crossing when a train travels thereover, and likewise movable to close the crossing through the railroad to prevent trespassing thereon and accidents which result therefrom.

A further object is the provision of a railway crossing gate adapted by its construction to be swung in a horizontal plane to extend crossways of the track in its normal position and when the crossing is to be barricaded and wherein the construction is such that all of the gates constituting the improvement will be simultaneously swung by the operation of a single crank or lever, wherein the parts are strongly constructed to withstand the strain of wind directed thereagainst, wherein the gates have anti-frictional elements that travel on tracks and wherein all of the operating parts are effectively housed and concealed and thereby protected from weather conditions.

A further object is the provision of a safety railway gate which is swingable in a horizontal plane either transversely of the street or crossing or transversely of the railroad, and which in the turning thereof will operate audible signals and illuminate lamps to warn traffic as to the position of the gates.

To the attainment of the foregoing the improvement further resides in certain other novel features of construction, combination and operative association of parts, one satisfactory embodiment of which is disclosed by the accompanying drawings.

In the drawings:

Figure 1 is a plan view of my improvement.

Figure 2 is a transverse sectional view approximately on the line 2—2 of Figure 1.

Figure 3 is a detail sectional view approximately on the line 3—3 of Figure 1.

Figure 4 is a horizontal sectional view approximately on the line 4—4 of Figure 2.

In the drawings the numeral 1 designates

a street or roadway, and 2 the rails of a track which cross the street or roadway.

At the opposite sides of the railway track, and likewise at the opposite sides of the street or roadway 1 I arrange my improved gates. At these points I arrange in openings in the ground substantially rectangular box-like members or wells 3 which are preferably constructed of concrete and project a slight but suitable distance above the road surface. 55 The oppositely disposed pairs of wells 3 are connected by conduits 4 which are let in the ground below the railroad track while two of the said wells 3 are connected by another conduit 5 which is arranged transversely on or below the street or roadway 1. Fixed in the bottom of each of the wells there is a bearing 6 for the lower end of a vertically disposed shaft 7. Each shaft 7, at the portion thereof received in the well 3 has fixed 60 thereon a drum 8 and trained around the drums 8 and guided through the conduits 4 65 there are crossed belts or cables 9.

Bolted or otherwise removably secured by means 10 to the upper edges of the wells 3 75 there are hollow castings in the nature of base members 11. These base members have closed tops, each of which being formed with a circular track 12. Each of the closed tops of the base members 11 is provided with a central bearing opening for the respective shaft 7, and the said shaft is removably secured by means 13 to the central and bottom portions of an upright and post 14. The posts 14 have their bottom portions widened 80 and formed with inner and outer depending annular flanges 15 and 16, respectively. Received between these flanges there are rollers 17 whose stub shafts or trunnions 18 are journaled in bearing openings in the said 85 flanges. The rollers rest on the rails on tracks 12.

Preferably the posts 14 are of metal as are the base members 11, and the said posts being also preferably provided with right angularly extending ribs which reinforce the center thereof and to one of each of these ribs there is fixed the inner end of a truss frame 19 that provides a gate or barrier. The outer ends of the truss frame 19 has semi-circular 90 95 100

extensions 20 on which are imprinted the words "Stop", "Safety first" or any other desired warning signal and in the semi-circular ends of one of each pair of gates 19 there is fixed a warning lamp 21 which is illuminated when the gates are swung to provide a barrier for the street or crossing or a barrier for the railroad. The posts 14 may and preferably are ornamental and the top of each post carries a globular shade 22 for a lamp which is illuminated in the night time, the said lamps not being shown. In this connection it may be stated that the warning lamp 21 is illuminated only in the night time and the bulb of the said lamp as well as those in the globes 22 are automatically illuminated by suitable switch mechanism, (not shown), that completes circuits to the bulbs from suitable batteries, also not shown.

One of the wells is of a greater length than the remainder and likewise the base or casting for this well is of a greater length than the remaining base members. For distinction, this well is indicated by the numeral 3', and the base or casting thereon by the numeral 11'. Also for distinction the gate operating shaft in this well and base is indicated by the numeral 7'. The well 3' has connected thereto the conduit 5. In addition to the shaft 7' there is journaled between the well 3' and the base member 11' therefor another shaft 23. On this shaft there is fixed a drum 24 and trained around this drum is the straight cable 9. On the shaft 23 there is a toothed wheel 26 that is in mesh with a similar wheel 27 that is fixedly secured on the shaft 7'. On the shaft 7' there is fixed a worm gear 26' and in mesh with the teeth of this gear 26' there is the worm 27' on a shaft 28 that is journaled through suitable bearing openings in the base 11'. One end of the shaft 28 is designed to have removably connected therewith an operating crank handle 29. The shaft 7', below the wheel 27 has fixed thereon a drum 25 around which there is trained a twisted endless belt or cable 25' which is directed through the transverse conduit 5 and is trained around the pulley 8 on the shaft 7 in the well 3 opposite the well in which the shaft 7' is journaled, or in other words, the straight endless belt or pulley 25' is received in the pulleys in the wells that are connected by the conduit 5.

Base castings are really in the nature of comparatively small towers and it will be apparent after the foregoing description has been carefully read in connection with the drawings that the turning of the crank 29 will impart a turning to the shaft 7' which, through the medium of the cross belts or cables and the drums in the respective wells and conduits and impart a horizontal swinging to the gates or barriers 19 to bring the

same either transversely across the roadway 1 or across the rails of the track 2 as disclosed by the full and dotted lines in Figure 1 of the drawings. The base or tower 11' is arranged conveniently with respect to the house or box for the gate keeper.

It will be noted from the foregoing that I have produced a comparatively simple but strong, easily operated and thoroughly effective crossing gate that affords a barrier for either a roadway or street and a railway track. It will be further noted that the gate posts, when illuminated will indicate to travelers either on the roadway or occupants of the rolling stock for the railroad, especially the engineer or fireman that a railway crossing is directly ahead. In addition to the lamps on the gate posts and the signal lamps 21, audible alarms such as bells may be sounded when the gates are swung to either of their positions. Such arrangement, and other details of construction, such as fall within the scope of what I claim may be resorted to without departing from the spirit of the invention.

Having described the invention, I claim:

A gate construction comprising a well adapted to be embedded in the ground, a hollow casting supported by the well above the ground and secured thereto, said casting including a top wall having a centrally located bearing, a shaft rotatably supported within the well and having at its upper end journaled in and projecting above said bearing, a circular track rising from the top wall of the casting, a post arranged above the casting and having a centrally located bearing to receive the adjacent end of said shaft, a gate supported by the post, means for rotating the shaft in reverse direction to open or close the gate, the lower portion of the post being relatively wide and formed with inner and outer depending annular flanges, and rollers journaled between said flanges and movable over the circular track of the casting.

In testimony whereof I affix my signature.

JOSEPH ARTHUR DROUIN.
